Patented Oct. 16, 1917.

FIG. 4.

FIG. 5.

UNITED STATES PATENT OFFICE.

HORATIO G. GILLMOR, OF WASHINGTON, DISTRICT OF COLUMBIA.

ANTICREEPER.

1,243,282.

Specification of Letters Patent. Patented Oct. 16, 1917.

Application filed April 17, 1916. Serial No. 91,617.

To all whom it may concern:

Be it known that I, HORATIO G. GILLMOR, a citizen of the United States, residing at Washington, in the District of Columbia, 5 have invented new and useful Improvements in Anticreepers, of which the following is a full, clear, concise, and exact description, reference being had to the accompanying drawing, forming part of this specification.

10 My invention relates to improvements in anticreepers, anchors or stays for railroad rails.

The chief object of my invention is to provide a light, simple and inexpensive anti- 15 creeper which may be readily and securely applied to the rail base and which is effective in resisting creeping.

Other objects are to provide an improved anticreeper constructed in one piece; to provide an anticreeper of this type having improved means for holding it to the rail base; to provide an anticreeper which does not work loose after being applied but which may be readily removed if desired and to 25 provide an anticreeper which operates with the maximum of efficiency under all conditions.

In the accompanying drawings, I have illustrated a preferred form of the invention, in which:

Figure 1 is a side view of the anticreeper showing a portion of the rail in side elevation. Fig. 2 is a rear view of the anticreeper showing the rail in section. Fig. 3 is a plan view thereof showing a portion of the rail. Fig. 4 is a front view thereof after the device has been placed upon the rail and before being locked in operative position upon the rail which is shown in section. 30 Fig. 5 is a rear view of the anticreeper in one of the positions assumed when applying the device to the rail which is shown in section.

Similar letters refer to similar parts throughout the several views.

5 In Figs. 1, 2 and 3 is shown a rail A of the usual type, having a head B and a base flange C resting upon one of the usual cross-ties D. The anticreeper or rail anchor E extends transversely underneath the rail base and is provided at one end with an arm F, extending upwardly and inwardly and adapted to engage the upper surface of the rail base flange C at one side of the rail at G. The portion of this arm F extending over the base flange C is preferably beveled as at H, Fig. 2 and at the other end of the

anticreeper E there are two portions I and K at opposite sides of the transverse portion of E arranged to engage the edge of the rail base flange. The portions I and K may be formed with teeth or serrations L. The end of the anticreeper E opposite to the arm F is also provided with a portion M which extends upwardly and inwardly from E and has surface N arranged to engage the upper surface of the rail base flange C and surface O arranged to engage the under side of the head B of the rail. The portion M is so formed that, in its normal condition, the angle between the surface N and the body 70 of the anticreeper is greater than the angle of the top of the rail base flange C to the bottom of the rail base as illustrated in Fig. 4. The body portion of the anticreeper E has a portion with surface P arranged to 75 engage the bottom of the rail when the anticreeper is in operative position on the rail and a beveled portion Q which is out of contact with the rail bottom. At the opposite ends of the anticreeper E are two tie 80 engaging portions R and S, strengthened by ribs T and arranged to extend forwardly at the lower portion as at U, in Fig. 1. The portion I is beveled at the upper part as at V, Fig. 2, and the portion K is beveled at 85 the bottom as at W, Fig. 4. The surface X on the arm F forms a shoulder engaging the edge of the rail base. The webs Y strengthen the connections of the portions of the anticreeper one with the other. 90

To place the anticreeper in position upon the rail, it is placed transversely beneath the rail base and rotated through such an angle as will bring the portion I below and the portion K above the rail base flange C. 95 With the anticreeper in this position the arm F can be brought to a position beyond the edge of the rail base flange C at the side thereof opposite to that above and below which the portions I and K of the anticreeper are. 100 This position of the anticreeper is illustrated in Fig. 5. From this position illustrated in Fig. 5, the anticreeper E may be drawn transversely of the rail until the beveled portion H of the arm F engages the top of the rail base flange C, when by turning the anticreeper so that the portion M will be vertical the portions I and K will be brought into engagement with the edge of the rail base flange C at the side of the rail opposite to 105 that engaged by the arm F. The beveled surfaces V and W of the portions I and K

will during this turning of the anticreeper E act with a cam action upon the rail edge so that in the final position of the anticreeper E with the portion M vertical the rail will be gripped transversely between the shoulder formed by the surface X of the arm F and the portions I and K. The teeth or serration L on the portions I and K are provided so that if the rail should be wider than the usual or standard width, there may be some upsetting of these teeth or serrations and the deformation of the teeth thus adjust the distance between the surface X and the portions I and K of the anticreeper to the wider base flange. The anticreeper, after the movements referred to above, will occupy the position illustrated in Fig. 4; and in this position the surface P of the transverse portion of the anticreeper E will engage the bottom of the rail base and the surface N of the vertically disposed portion M will engage the upper corner of the edge of the rail base flange C at Z.

To effectually grip the anticreeper upon the rail and maintain it in operative position upon the rail the vertically disposed portion M is driven in toward the rail and wedged in between the under side of the head B and the upper surface of the base C of the rail. The anticreeper is preferably constructed of such material as malleable iron which has a certain amount of resiliency but may also be deformed and in driving the upper portion of the portion M toward the rail, by force applied near the top, it tends both to spring and to deform and there is exerted an upward pressure of the surface O of the portion M upon the under side of the rail head B and a downward pressure of the surface M upon the top of the rail base C and at the same time the anchor as a whole tends to move angularly slightly pivoting upon the upper surface of the rail base flange C where it is engaged by the surface N of the portion M and the surface P of the transverse portion of the anticreeper E is thus pressed upwardly against the bottom of the rail base C. In the final operative position of the anticreeper, the rail is gripped transversely between the portions I and K and the surface X of the arm F and vertically between the surface G of the arm F and the surface N of the portion M and the surface P of the anticreeper E extending transversely beneath the rail; and, at the same time, the vertically disposed portion M is driven tightly in between the rail head B and the rail base C. The anticreeper is thus made to effectually grip the rail and is efficiently locked in position upon the rail so that it will at all times efficiently resist any tendency of the rail to move forward in the direction of the arrow in Fig. 1. Movement of the rail in the reverse or backward di-

rection will not loosen the device upon the rail even though the tie engaging portions R and S should be held because of the wedging engagement of the vertically disposed portion M of the device with the head B 70 and the base flange C of the rail.

The device is readily removed from the rail by forcing the upper portion of the vertically disposed portion M out from the rail to the position illustrated in Fig. 4 and 75 then forcibly rotating the whole anticreeper E until the portion I is below and the portion K is above rail base flange C when the anticreeper E may be removed from the rail.

It is obvious that various changes may be 80 made in the structure described, without departing from the spirit of the invention. The device need not necessarily be made as a casting, but of other material than cast material. I desire therefore to cover in the 85 appended claims whatever modified structures fall within the scope of the invention.

Having thus described my invention what I claim as new and desire to secure by Letters Patent of the United States is:

1. An anticreeper, comprising elements gripping the rail base flange at opposite sides thereof, a tie-abutting flange and a vertically disposed element arranged to be driven in between the bottom of the head 95 and the upper surface of the base flange of the rail.

2. A rail anchor, comprising a transverse element engaging the rail bottom, a tie-abutting element, and two elements arranged to 100 engage the upper surface of the base flange of the rail at opposite sides of the rail forward of the engagement of the transverse element with the bottom of the rail, one of said elements having a vertical projection 105 constructed to be forced in between the head and base flange of the rail.

3. An anticreeper constructed with a rail base edge engaging element at one end and a plurality of rail base edge engaging elements at the other end so arranged that angular movement of the anticreeper about an axis transverse to the rail produces a wedging and gripping action of said elements upon opposite edges of the rail base. 110

4. An anticreeper, comprising a transverse bar adapted to engage the bottom of the rail base flange and arms at each end thereof, in vertical and horizontal spaced relation to said transverse bar, adapted to 120 engage the upper surface of the rail base flange and means engaging the under side of the rail head for effecting the gripping action and locking of the anticreeper in position.

5. A rail anchor, comprising a bar engaging the bottom of the base flange of the rail, tie engaging means at opposite ends of said bar, arms at opposite ends of said bar for engaging upper surfaces of the rail base 130

flange at opposite sides of the rail and a rail head engaging projection for locking the anchor in operative position on the rail.

6. A one piece anticreeper having a rail edge engaging shoulder at one end, a plurality of rail edge engaging shoulders at the other end and a vertically disposed portion arranged to be driven in between the rail head and the rail base flange.

10 7. An anticreeper, comprising a transverse bar provided with a rail base edge engaging portion and a tie engaging portion at one end and, at the other end thereof, rail base edge engaging portions at opposite 15 sides of said transverse bar and an upwardly and inwardly extending portion constructed to be driven in between the rail head and the rail base flange.

8. A rail stay, comprising a bar constructed to engage the bottom of the base flange of a rail, provided with an arm at one end adapted to engage the upper surface of the base flange of the rail and provided at the other end with a tie-abutting flange and 25 an arm adapted to engage the upper surface of the rail base and the under surface of the rail head.

9. An anticreeper constructed with cam surfaces adapted to engage and grip opposite edges of a rail base flange, a transverse cam surface engaging the bottom of the rail and a tie-engaging flange and two arms adapted to engage the upper surface of the rail base flange in spaced relation to said 35 transverse bottom engaging cam surface, one of said arms having an upwardly extending portion adapted to engage the under side of the rail head at one side of the rail.

10. A rail anchor constructed with rail base edge engaging portions adapted to grip opposite edges of the rail base flange, arms adapted to engage the upper surfaces of the rail base flange at opposite sides of the rail and tie-abutting portions all connected by 45 a transverse portion provided with rail base bottom engaging surfaces and a vertically disposed portion arranged to be driven in between the head and base flange of the rail at one side.

50 11. A rail anchor, comprising a transverse bar engaging the bottom of the rail base, an arm at one end of the bar adapted to engage the upper surface of the rail base flange and, at the other end of said bar, a tie-engaging flange; and in spaced relation to said bar and tie-engaging flange, an arm constructed to engage the under side of the head and the upper surface of the rail base flange.

60 12. A rail anchor comprising a body portion extending beneath the rail base flange, means for engagement with a tie, means for engaging and gripping opposite edges of the rail base flange when said anchor is 65 moved angularly about an axis transverse to

the rail and means for locking said anchor in gripping engagement with the rail.

13. An anticreeper comprising opposing elements for engagement with opposite edges of the rail base and adapted to be 70 brought into engagement therewith by rotation of said anticreeper about a transverse axis, means for holding said element in engagement with the rail base and means for engagement with a fixed portion of the 75 roadbed.

14. A device for preventing the creeping of rails, comprising opposing elements for engagement with opposite edges of the rail base arranged to be forced into gripping 80 engagement with the rail base by angular movement about a transverse axis, said elements having portions which may be deformed to adapt the device to varying widths of rail base, and means for giving 85 the device a fixed position in the roadbed in opposition to the tendency of the rail to creep.

15. A rail anchor, comprising opposing shoulders for engagement with opposite 90 side margins of the rail base, those at one side of the rail having surfaces oppositely inclined from the vertical and so disposed in relation to the opposing shoulder that rotation of the anchor will effect a gripping of 95 the rail base between the opposing shoulders, and means for engagement with a fixed portion of the roadbed.

16. An anticreeper, comprising opposing abutments for engagement with opposite 100 vertical edges of the rail base, those at one side of the rail having deformable portions to allow for varying widths of rail base and surfaces oppositely inclined from the vertical, arranged to be brought into gripping 105 engagement with the rail base edges by rotation about an axis transverse to the rail, and means for engaging a tie in opposition to the tendency of the rail to creep.

17. An anticreeper constructed with a 110 rail base edge engaging element at one end and a plurality of rail base edge engaging elements at the other end provided with cam surfaces, said elements being so disposed that angular movement of the anticreeper 115 about an axis transverse to the rail produces a cam action and gripping of opposite edges of the rail base by said elements and means for engaging a fixed portion of 120 the roadbed.

18. A device for preventing the creeping of rails, comprising a transverse bar having opposing abutments for engagement with opposite side margins of the rail base constructed with deformable portions arranged 125 to be changed in shape when said device is forced into position to provide for variations in the width of the rail base.

19. An anticreeper constructed with a rail base edge engaging element at one end and a 130

4

plurality of rail base edge engaging elements at the other end so arranged that angular movement of the anticreeper about an axis transverse to the rail produces a wedging and gripping action of said elements upon opposite edges of the rail base, and provided with means for engaging a fixed portion of the roadbed.

20. An anticreeper comprising opposing elements for engagement with opposite edges of the rail base and adapted to be brought into engagement therewith by rotation of said anticreeper about a transverse axis, means engaging the under side of the rail head for holding said elements in gripping engagement with the rail base and means for giving the anticreeper a fixed position in the road bed in opposition to the tendency of the rail to creep.

21. A rail anchor comprising a transverse bar adapted to engage the bottom of the rail base flange and arms at each end thereof, in vertical and horizontally spaced relation to said transverse bar, adapted to engage the upper surface of the rail base flange, means engaging the under side of the rail head for effecting the gripping action and locking the anticreeper in position and means for engagement with a fixed portion of the road bed.

22. A one piece anticreeper having a rail edge engaging shoulder at one end, a plurality of rail edge engaging shoulders at the other end, a vertically disposed portion arranged to be driven in between the rail head and the rail base flange and a tie engaging flange.

23. An anticreeper, comprising opposing elements for engagement with opposite edges of the rail base, and opposing elements for engagement with the bottom and top of the rail base all adapted to be brought into gripping engagement with the rail base by rotation of said anticreeper, and means for locking said anticreeper in position with said elements in gripping engagement with

opposite edges, the top and the bottom of the rail base.

24. An anticreeper, comprising opposing elements for engagement with opposite edges of the rail base and opposing elements for engagement with the bottom and top of the rail base all adapted to be brought into gripping engagement with the rail base by rotation of said anticreeper, means for engagement with a fixed portion of the road bed and means for holding said elements in gripping engagement with the rail base.

25. A rail anchor comprising opposing walls for engagement with opposite side margins of the rail base and opposing elements for engagement with the top and bottom of the rail base so arranged that rotation of the device will cause the rail base to be wedged between the opposing walls and the top and bottom of the rail base to be gripped by said opposing elements, means for holding said anchor in position and means for giving said anchor a fixed position in the road bed.

26. An anticreeper comprising opposing elements for engagement with the top and bottom of the rail base, a shoulder for engagement with one vertical edge of the rail base, shoulders with faces oppositely inclined to the vertical for engagement with the other edge of the rail base, means for retaining the opposing elements and shoulders in engagement with the top and bottom and opposite vertical edges of the rail base and means for giving the device a fixed position in the road bed.

27. A rail anchor, comprising a body portion extending transversely beneath the rail base flange, means for engagement with a tie, means for engaging and gripping opposite edges of the top and the bottom of the rail base flange when said anchor is moved angularly about an axis transverse to the rail and means for locking said anchor in position upon the rail.

H. G. GILLMOR.
